DESIGN FOR A CAPE.

Design No. 6,643, dated May 6, 1873

UNITED STATES PATENT OFFICE.

MARTIN LANDENBERGER, JR., OF PHILADELPHIA, PENNSYLVANIA.

DESIGN FOR A CAPE.

Specification forming part of Design No. **6,643**, dated May 6, 1873; application filed April 8, 1873.

To all whom it may concern:

Be it known that I, MARTIN LANDENBERGER, Jr., of Philadelphia, Pennsylvania, have invented a Design for a Garment, of which the following is a specification:

The figure in the accompanying drawing clearly represents my design for a garment.

The garment is of somewhat greater width and of less depth than ordinary circulars, and instead of being made on a continuous curve is formed on two comparatively flat curves, *a*, meeting at a point, *b*, at the bottom of the garment, the latter being in the present instance slashed upward from this point. The hood *B* is of the peculiar shape clearly shown in the drawing, is ornamented by a deep fringe, *c*, similar to that secured to the curved edge of the garment by an inner narrow fringe, *d*, a row of buttons, *e*, and a tassel, *f*.

Irrespective of the colors employed, I claim—

1. The design for the garment having the outline, substantially as described and represented.
2. The design for the hood having the outline, substantially as shown and described.
3. The design for the whole garment with its minor ornamentation, substantially as described and as represented in and by the accompanying drawing.

In testimony whereof I have signed my name to this specification in the presence of two subscribing witnesses.

MARTIN LANDENBERGER, JR.

Witnesses:

J. J. BUCHEY,
JNO. JAY WARD.
